US0D1018602S

(12) **United States Design Patent** (10) **Patent No.:** **US D1,018,602 S**
(45) **Date of Patent:** **** Mar. 19, 2024**

(54) **BUCKET SHROUD**

(71) Applicant: **Caterpillar Inc.**, Peoria, IL (US)

(72) Inventors: **Nathan Bjerke**, Peoria, IL (US);
Thomas Marshall Congdon, Dunlap,
IL (US)

(73) Assignee: **Caterpillar Inc.**, Peoria, IL (US)

(**) Term: **15 Years**

(21) Appl. No.: **29/891,716**

(22) Filed: **May 9, 2023**

Primary Examiner — Mark A Goodwin

(57) **CLAIM**

The ornamental design for a bucket shroud, as shown and described.

DESCRIPTION

FIG. 1 is a perspective view of a bucket shroud showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines depict portions of the bucket shroud which form no part of the claimed design.

The dot-dash broken lines depict boundaries which form no part of the claimed design.

1 Claim, 5 Drawing Sheets
